WELL GRAVELING AND DEVELOPING ASSEMBLY AND METHOD

Leslie A. Layne, Houston, Tex., assignor to The Texas Company, a corporation of Delaware

Application June 21, 1937, Serial No. 149,400
Renewed August 4, 1938

12 Claims. (Cl. 166—21)

The invention relates to a general assembly of equipment to be used in the graveling and developing of oil, gas or other high pressure wells.

In the drilling of wells under pressure it is desirable to increase the production as much as possible and to this end the well bore may be enlarged in diameter adjacent the productive formation so that a greater drainage area is provided into the well bore for the desirable fluid.

10 In order to form this excavation to enlarge the well bore the formation must be removed and filter beds of gravel or other granular material may be formed in the well bore about the well strainer so that the finer sands from the formation will be filtered out of the fluid before it reaches the strainer.

Another object is to gravel a well under pressure.

Another object is to underream a well where pressure is effective and to thereafter deposit gravel in the underreamed chamber.

Another object is to control a well under pressure while gravel is being added thereto.

Another object is to rework depleted wells by underreaming and graveling.

Still another object is to provide a closed gravel chamber in a well bore.

Still another object is to provide a circulating system for wells to prevent the sticking of tools therein and to facilitate their recovery in event of sticking.

It is one of the objects of the invention to circulate liquid down into the well bore and either mechanically or hydraulically underream or 35 move sand to enlarge the well bore; and it is usual for the downward stream to flow at a high velocity through a small diameter pipe and the return flow to pass through a larger diameter pipe at a slower rate but under these circumstances it has been found that the sand and other sediment in the returning liquid will sometimes settle back into the well bore, and to obviate this, the present invention concerns itself with an arrangement whereby an additional flow of liquid 40 may be combined with the returning column of liquid in the well so as to increase the rate of flow with the resultant carrying upward of the sand or other material.

It is one of the objects of the invention to 50 combine a circulation of liquid with the carrier liquid which is used in the graveling and developing of wells so as to increase the rate of the return flow from the well.

Another object of the invention is to provide 55 an arrangement of piping in a well in such a

combination that a carrier liquid containing gravel may be directed downwardly into the well to deposit the gravel about the screen and to thereafter return upwardly through the well carrying a load of sand or sediment from the formation in such a manner that the return flow may be supplemented by an additional circulation of liquid to assist in raising the sand or sediment to the surface.

Another object of the invention is to provide 10 an apparatus for graveling and developing of wells whereby the well may be closed in very quickly in event of excessive pressure from the formation.

Other and further objects of the invention will 15 be readily apparent when the following description is considered in connection with the accompanying drawings, wherein:

Fig. 1 is a side elevation of a well bore illustrating certain of the parts in section to show 20 the general arrangement thereof.

Fig. 2 is a view of the top portion of the well above the parts shown in Fig. 1 and illustrating the manner of combining the two circulating streams of liquid and closing the upper end of 25 the well bore.

Figs. 3, 4 and 5 are sections taken on the line 3—3, 4—4, and 5—5 of Fig. 1, respectively.

Fig. 6 is a diagrammatic view showing a side elevation of the apparatus and equipment in operating position.

The general assembly of all of the equipment is best seen in Fig. 6 and in this view the well bore is indicated generally at 2. The producing formation is adjacent the elevation 3 where the 35 well bore has been enlarged in order to receive the filter bed of granular material 4. In some instances this enlarged area 3 is formed by underreaming with any type of mechanical tool and in some instances it is formed by hydraulic circulation of liquid so as to carry the formation out of the well bore.

The apparatus generally which is utilized in the construction after the enlargement has been formed is the set shoe 5 to which the strainer 45 6 and the liner 7 have been connected. The graveling tool is shown in the housing 8 in the upper end of the liner at 9. This liner projects into the lower end 10 of the casing 12, which may be cemented at 13 into the well bore above the 50 producing formation in order to form a seal. A production string 15 extends downwardly into the well bore to an elevation closely adjacent the upper end of the liner 9 and this string of pipe is supported by a hanger 16, which is locked in 55

position by the bolts 17 in the casinghead 18, if desired.

An inlet pipe 19 is connected to the discharge 20 of the pump 21 so that a flow of fluid may be directed to the area 22 between the casing 12 and the production string 15. This flow of fluid will move downwardly thru the area 22 and around the lower end of the pipe 15 and thence upwardly into the area 25 inside of the production string 10 so that it will discharge from the port 26 into the pipe 27. The upper end of the production string is closed by a head 30 which carries a stuffing box 31 to form a seal about the graveling string 32. This graveling string in turn leads to the piping 33 and thence to the graveling apparatus 35; a bypass 35' leads around the apparatus so as to control the flow. A pump 34 supplies liquid under pressure to the apparatus.

In operation a fluid will be circulated into the inlet 36 of the graveling apparatus where it may or may not pick up the gravel, depending on whether it is directed thru the bypass 35'. This stream is then directed to the pipe 33 and downwardly into the well bore where it discharges from the graveling tool 8. If this stream carries particles of gravel they will be deposited as seen in Fig. 6 and the liquid will then pass through the strainer 6 and upwardly through the liner 9 into the production string 15. Naturally this circulation will pick up sand and sediment from the formation 3 and it has been found that when this carrier liquid emerges from the graveling tool 8 into the liner 9 and the production string 15, its velocity of flow is diminished. At this stage of the operation the pump 21 will be used to discharge liquid downwardly to the chamber 22 so that it will pass around the lower end of the production string 15 and upwardly into the chamber 25 in this string.

With this supplemented flow of liquid, the rate of flow will be increased with the result that the sand and sediment will be carried along with the liquid and discharge from the pipe 27. This results in a better filter bed because of the carrying away of sand and sediment and also prevents clogging of the apparatus in the well.

Referring now to the various parts of equipment, the shoe 5 is shown specifically in Fig. 1 and is surmounted by the strainer or screen 6. Above this strainer is the blank pipe or liner 7, which in turn connects to the graveling tool housing 8.

The graveling tool, per se, forms no part of the present invention except where it is in combination with the other parts and is fully described in the application for patent of Leslie A. Layne and Harold C. Block, Serial No. 62,028, filed February 3, 1936.

In order to understand the operation of this tool, it will be described briefly as including the outside pipe or housing 40, which is telescopically arranged in the coupling 41 on the liner 7. A shoulder 42 in the liner 7 supports the break-out ring 43, which is best seen in Fig. 5, as being grooved at 44 so as to permit its being fractured after the graveling operation has been completed.

This break-out ring 43 supports the shoe 45 or dental clutch of the lower end of the graveling tube 46. This clutch may be semicircular as seen in section in Fig. 5 so as to orient the graveling tool in the housing 40 when it is turned so as to settle in upon the break-out ring. The tail or wash pipe 47 may be carried by the lower end of the tube 46 so that the well might be produced directly through the tool if desired.

The tube 46 serves as a support for the packer or seal 48 which forms part of the graveling tool and is provided for the purpose of forming a seal about the gravel discharge pipe 49 which extends through the port 49' in the housing 40. The packing 48 is compressed by means of a setting sleeve 50, which is telescopically arranged on the gravel tube 46 and is moved downwardly by the head 52 thereon, which is connected to the lower end of the gravel line 32. When some of the weight of the gravel line 32 is applied to this head 52, it will move the setting sleeve 50 downwardly so as to expand the packing. The upper end of the setting sleeve 50 is grooved at 54 in order to allow a circulation of liquid upwardly through the gravel tube 46 around the gravel discharge pipe 49 and thence into the upper end of the liner 9.

A coupling 56 serves to connect the graveling tool housing 8 with the upper portion of liner 9 and the lower end of this coupling may be provided with a sealing material 57 such as lead, which is arranged to form a seal with the shoulder 58 on the upper end of the liner 7. It seems obvious that a sharp dropping of the gravel line 32, a string of drill pipe, or any desired object will impart a sufficient shock to the break-out ring 43 to fracture it so that it will drop out of position and permit the liner 9 and the packer 70 to move downwardly. Thus, the sealing material 57 will engage the shoulder 58. This telescoping movement will be accomplished, of course, after the graveling operation has been completed and the well has been fully developed for the purpose of closing up the discharge port 49' through which the gravel has been discharged.

It will be understood that as previously described there is a circulation of liquid downwardly through the graveling string 32, the discharge port 49 and outwardly into the well bore. If this liquid carries gravel it will be deposited in the well bore and the liquid will then enter the screen 6, carrying with it any sand or sediment. It will enter the wash pipe 47, the gravel tube 46, and pass through the slots 54 into the chamber 60 in the upper end of the liner 9 and thence upwardly into the production string 15.

As previously described, the additional circulation from the pump 21 will flow downwardly through the chamber 22 and merge with this stream of liquid moving upwardly from the chamber 60. In order to prevent the flow of fluid downwardly into the producing formation from the casing 12 a packer 70 has been provided on the upper end 9 of the liner 7. This packer includes a support pipe 71, the packer support 72, and the packing 73. This packing is arranged for expansion due to the telescoping movement of the setting sleeve 74. This sleeve may be set by manipulation of the production string 15 or in any other desired manner.

In operation, it is contemplated that either liquid or liquid and gravel may be circulated through the graveling apparatus downwardly into the well bore to wash out a cavity for the gravel. The cavity may be preferably formed by mechanical underreaming or it may be formed by circulating the liquid with the gravel in it into the well bore carrying with it sand formation by the returning carrier liquid.

In any event it is usual for the return liquid to be carrying sand and sediment and it is intended that the rate of flow of this return stream which is laden with sand and sediment will be increased due to the provision of the additional

circulating stream of liquid from the pump 21.

To assemble and operate the mechanism the set shoe 5, the screen 6, liner 7 and the gravel gate assembly 8 with the break-out ring 43 and the packer 22, are set in the well in the usual manner with the shoe 5 on the well bottom, and after the setting string is released the packer 22 is partially collapsed and the setting string is removed. Such setting string may be the production string 15 or any other suitable string of pipe. The gravel tool and packer assembly 48 are next lowered into the well by means of the tubing 32 and oriented by means of the dental clutch 45 on the bottom thereof, engaging the corresponding parts on the break-out ring 43. The flow string 15 is next lowered into the well until the bottom of the flow string is just slightly above the top of the liner portion 9.

It is possible to alter this procedure by running the gravel tool assembly into the well on the flow string 15, in which case there would be ports through the walls of the pipe 15 just above the liner packer 9. The tubing string 32 would then be run into the well and engaged with the gravel tool assembly.

After the graveling operation has been completed the tubing 32, the gravel tool assembly, and the flow string 15 are removed from the well and a string of drill stem or tubing is then run into the well and the break-out ring 43 is broken out, and the gravel gate mandrel 8, the collar 51, and the liner portion 9, are all moved downwardly until the lead seal 57 contacts the shoulder 58, thus closing the gravel gate. The liner portion 9 is then completely set by additional downward movement and the well is completed.

While the term "gravel" has been applied to the divided material to be deposited, it is to be understood that such term may include any suitable granular or divided material which will form a filter bed. The oil string or development pipe string 15 may be omitted in some instances or the added circulation forced through the graveling string.

Broadly, the invention contemplates that the graveling and developing of a well may be carried on under heavy pressures encountered in oil wells so that the pressures may be controlled during the operation, and that oil or gas wells may be underreamed to provide space for the gravel regardless of whether they are new wells or wells being reworked.

What is claimed is:

1. An apparatus for completing wells comprising a well casing, an oil string therein, a well bottom assembly including a set shoe, a strainer and a packer to be set to form a seal with said casing, a graveling string and tool to discharge gravel around said screen, means to circulate liquid and gravel down said gravel string and to return the carrier liquid upwardly through the well bottom assembly into said oil string, and additional means to circulate liquid down said casing and into said oil string to facilitate the return circulation of the carrier liquid.

2. In a well graveling and developing assembly a plurality of strings of pipe in the well, means to direct a carrier liquid down one string, means to direct a circulating liquid down another string, and a third string to receive the combined return of both of the other two strings so that the rate of return flow through said third string will be at a greater rate so as to carry divided material from the well.

3. An assembly for graveling and developing

wells which comprises in combination a well casing, a pump connected to discharge liquid into said casing, a valve in said connection, a casing head on said casing and a production string of pipe supported therein, a discharge from said pipe, a valve in said discharge, a graveling line inside of said string, graveling apparatus connected to said line, and a valve in said line, the closing of said valves serving to completely close in the well.

4. An assembly for graveling and developing wells which comprises in combination a well casing, a pump connected to discharge liquid into said casing, a valve in said connection, a casing head on said casing and a production string of pipe supported therein, a discharge from said pipe, a valve in said discharge, a graveling line inside of said string, graveling apparatus connected to said line, and a valve in said line, the closing of said valves serving to completely close in the well, a strainer at the bottom of said casing, a graveling tool on said graveling line to discharge gravel from said apparatus about said strainer, and a packer between said strainer and said casing so that the circulation from said pump and said apparatus will be combined to return through said production string.

5. In a well graveling and developing assembly including a casing, a return string of pipe, a graveling line and a strainer, the combination of a seal between said casing and strainer, the lower end of said production string being open to said casing and to the top of said strainer, a pump to circulate liquid or liquid and gravel downwardly through said gravel line so as to displace sand from the formation which will be carried into said production string by the return circulation, and means to supply an additional circulation downwardly through said casing to be combined with the first return circulation so as to increase the rate of flow of the returning circulation whereby the sand is carried from the well.

6. In combination with a well strainer, a graveling tool, means to discharge liquid and gravel therefrom and about said strainer, a return line for the liquid, and means including a casing in the well to direct an additional flow of liquid into said return line.

7. An apparatus for completing wells comprising a well casing, an oil string therein, a well bottom assembly including a set shoe, a strainer and a packer to be set to form a seal with said casing, a graveling string and tool to discharge gravel around said screen, means to circulate liquid and gravel down said gravel string and to return the carrier liquid upwardly through the well bottom assembly into said oil string.

8. In the art of preparing an oil well for graveling, the steps of underreaming the oil stratum below the casing to provide a gravel chamber, setting a screen in the gravel chamber, and sealing the space between the top of the strainer and the casing at the top of such chamber to provide a closed area about the screen to receive gravel.

9. In the art of graveling an oil well, the steps of underreaming the oil stratum below the well casing to provide a gravel chamber, setting a strainer in the enlarged chamber, sealing the space between the top of the strainer and the well casing, and further sealing the well at the casing head on top of the casing whereby control of the well pressures is possible, and filling the chamber with gravel.

10. A method of preparing an oil well for grav-

- eling, including enlarging the well bore at the producing stratum below the casing, setting a strainer pipe and liner in the enlarged well bore, sealing the space between the liner and the casing with a packer, providing an opening through the wall of the liner below the packer, and sealing the casing head on top of the casing whereby the well pressures may be controlled.
11. A method of preparing a gravel chamber in oil wells comprising the steps of underreaming the productive formation, setting a screen in the underreamed area, sealing around the top of the screen to close off the underreamed chamber

from the well bore thereabove, and depositing a body of gravel in such chamber.

12. An apparatus for completing wells comprising a well casing, a well bottom assembly including a set shoe, a strainer and a packer to be set to form a seal with said casing, a graveling string and tool to discharge gravel around said screen, means to circulate liquid and gravel down said gravel string and to return the carrier liquid upwardly through the well bottom assembly into an oil string.

LESLIE A. LAYNE.
